COMBINATION PUMP AND TANK FOR PORTABLE SPRAYER

Fernand Berthoud, 69220 Belleville-sur-Saone, France

Filed May 24, 1974, Ser. No. 472,951

Term of patent 14 years

Int. Cl. D23—01

U.S. Cl. D23—2

FIG. 1 is a top view of a combination pump and tank for a portable sprayer showing my new design.

FIG. 2 is a front view thereof.

FIG. 3 is a rear view thereof.

FIG. 4 is a bottom view thereof.

FIG. 5 is a side view thereof.

FIG. 6 is the side view opposite to that shown in FIG. 5.

I claim:

The ornamental design for a combination pump and tank for a portable sprayer, as shown.
